UNITED STATES PATENT OFFICE.

GEORGE F. WALKER, OF ARROYO, PENNSYLVANIA.

COMPOUND TOOL.

No. 868,733.

Specification of Letters Patent.

Patented Oct. 22, 1907.

Application filed January 21, 1907. Serial No. 353,297.

To all whom it may concern:

Be it known that I, GEORGE F. WALKER, a citizen of the United States, residing at Arroyo, in the county of Elk and State of Pennsylvania, have invented certain new and useful Improvements in Compound Tools, of which the following is a specification.

This invention is a compound tool of the hatchet type, and includes a hatchet, a hammer, a nail puller, and wrenches, all constructed and combined in a novel and improved manner.

The tool is illustrated in the accompanying drawings, in which

Figure 1 is a plan view thereof. Fig. 2 is an end view. Fig. 3 is a section on the line 3—3 of Fig. 1.

Referring specifically to the drawings, 6 indicates the handle of the tool. The head has on one side a hatchet blade 7 and on the other side a hammer head or poll 8, also a pair of claws 9 located opposite to the rear or distant edge of the hatchet.

The edge of the hatchet blade is serrated as at 10, and the face or edge of the claws opposite thereto is serrated as at 11, forming a tapering space therebetween which will receive a nut or pipe to be engaged by the serrations and turned by manipulation of the handle.

The hatchet blade is further provided with a diamond shaped opening 12 the edges of which are serrated, which can be used as a wrench on nuts and bolts. The blade also has in its inner edge a spike-pulling notch 13.

The poll 8 of the hammer has a threaded stem 14 which screws into an appropriate threaded socket in a neck 15 projecting from the body of the tool, and on one side the poll has an outwardly projecting or over-

hanging part 16 located opposite to one of the shoulders 17 on either side of the neck 15. The space between the parts 16 and 17 is adapted to receive a nut, and the construction forms a wrench whereby said nut can be turned. The size of the space or wrench can be varied by screwing the poll in or out. Also, the wrench can be formed on either side of the neck 15, since the poll 40 8 can be turned so that the overhanging part 16 projects either inwardly or outwardly, that is, either toward the handle or from the handle. This enables a nut to be got at in almost any position or under practically all conditions.

The handle is fastened or held in by means of a cap 18 and a screw 19 extending through the cap into the front end of the handle.

As will be seen from the end view, Fig. 2, the claws 9 are tapered or made so that their side faces coincide with the sides of the hatchet blade, whereby the hatchet can be used for splitting wood or the like without danger of the ends of the claws catching on the wood and interfering with the drive of the hatchet.

I claim:

A compound tool of the hammer type, having a neck projecting from the body thereof and shoulders on each side of the neck, and a poll having a screw connection to the neck, and a laterally projecting portion having a face parallel to the shoulders, the poll being rotatable to bring the said face of the projection opposite either shoulder, to form a wrench therewith.

In testimony whereof I affix my signature, in presence of two witnesses.

GEORGE F. WALKER.
